UNITED STATES PATENT OFFICE.

JOHN T. H. PAUL, OF CHICAGO, ILLINOIS, ASSIGNOR TO E. GOLDMAN & CO., INC., OF CHICAGO, ILLINOIS, A CORPORATION OF ILLINOIS.

BOTTLE-WASHER.

No. 876,657.

Specification of Letters Patent.

Patented Jan. 14, 1908.

Application filed May 4, 1907. Serial No. 371,835.

To all whom it may concern:

Be it known that I, JOHN T. H. PAUL, a citizen of the United States, residing at Chicago, in the county of Cook and State of Illinois, have invented a new and useful Improvement in Bottle-Washers, of which the following is a specification.

The present invention relates, more particularly, to improvements in features of the 10 bottle-washing machine shown and described in United States Letters Patent No. 827,388, granted to me on the 31st day of July, 1906.

The objects are to improve the step-by-step drive of the rotatory rack to the end of 15 rendering its motion smoother and avoiding the jar in starting and stopping the rack which attended its operation with the use of the former drive-means, and which tended to disorganize the mechanism of the machine, 20 with the additional consequent advantage of enabling the rack to be driven at greater speed than formerly; to provide the upper socket-members for the bottles with internal rotatory brushes to operate against the bottoms 25 of the inverted bottles for cleaning them; and to provide a simple and novel vertical adjustment for these upper socket-members, by which to readily adapt them to be raised and lowered and fastened in adjusted position, with relation to bottles of different lengths.

In the accompanying drawings, Figure 1 is a view of the improved bottle-washer in vertical sectional elevation; Figs. 2 and 3 are 35 sections taken, respectively, at the lines A and B on Fig. 1 and viewed as indicated by arrows; Fig. 4 is an enlarged broken view showing the bottle-bottom brush-mechanism in vertical sectional elevation, the section being taken at the line C on Fig. 3, and viewed in the direction of the arrow, in the 40 position of contact of the pinion with its depressing cam; and Fig. 5, a view in elevation of the ring in which the bottom-brush member is supported and which contains opposite angular slots for permitting the adjustment of the lower ring of the upper bottle-socket relative to the bottom-brush.

While the aforesaid patent shows and describes means for automatically delivering the washed bottles in succession to a traveling conveyer, these features, namely the delivery mechanism and conveyer, may or may not be employed and are omitted in this case 55 as having no bearing on the present improve-

ments, which relate to the rack-drive and the bottom-brush, as hereinbefore mentioned. The other parts of the machine are or may be the same as shown and described in the patent, so that it is only necessary to refer to them in the present connection in a general way, sufficient to enable the present improvements to be identified with the former construction.

The base-frame 6 is surmounted by the 65 pan 7 having a bracket 8 extending from one side and carrying on its upper end belted drive-pulleys 9 geared to the friction-drive 10 on the vertical shaft 11 of the rack 12, which shaft passes through the stationary 70 sleeve 13 and carries on its lower end the gear 14 for rotating the shafts of the internal brushes. The vertical shaft 15, journaled in the pan and in a horizontally extending frame-member 16, is geared by a crank-connection 75 at 17 with the vertically rocking cradle-device 18, which raises and lowers the internal brush-stems 19 with the chambered cross-head 20, to which these stems are connected at their lower ends, this shaft carrying 80 on its upper end the large gear-wheel 21 meshing with a pinion 22 on the shaft 11 and also carrying, between its ends, a gear 23 for rotating the external bottle-brushes 24 and actuating the friction-device 25 for the upper 85 rotary-socket members of the bottle-clamping devices. These socket-members constitute one of the features of improvement which will be more fully described hereinafter. The lower socket-members 26 for the bottle-necks 90 are movable on guide-rods 27 extending between the upper and lower heads of the rack, and are suspended by springs 28 from an adjustable crown-like hanger 29 on the sleeve 13 to be depressed by a cam 30 on the lower 95 end of the hanger. By moving into the lower part of a cam 31 on an extension of the frame-member 16, a stud 32 on a link 33 depending from the free end of the lever 34, the friction-drive 10 rotates the shaft 11 to produce 100 the several operations of the bottle-washer proper, including the opening and closing of a valve, at 35, by rocking the cradle-device 18, all as described in said patent.

To produce the requisite step-by-step rotation of the rack 12, with reference to which the rise and descent of the head 20 and the opening and closing of the valve 35 are timed, the following described mechanism is provided:

On the upper end of the shaft 15, between the gear 21 and the frame-member 16, which in the present case is of the shape represented in Fig. 2, is secured to rotate with it a disk 36 having its periphery formed with a concave arc-shaped recess 37, and provided with a crank-finger 38 extending across the center of said recess. An anti-friction roller 39 depends from the outer end of the crank-finger. Adjacent to the disk 36 is centrally journaled in the upper side of the horizontal frame-member a star-wheel 40 containing notches 41, shown as five in number, and equidistant apart, with concave arc-shaped recesses 42 in its periphery between notches conforming to the periphery of the disk 36. A gear-wheel 43 is provided below the star-wheel on its hub to mesh with an idler-pinion 44, which, in turn, meshes with a similar pinion 45 on a stub-shaft 46 journaled in the upper side of the frame-member 16 and carrying to extend with its ends equidistant from the axis of the stub-shaft, a cross-head 47 having studs 48, 48, which are preferably anti-friction rollers, depending from its opposite ends. On the top of the upper rack-head 50 near its periphery are provided in circumferential series teeth 49, of which eight are shown in Fig. 3, equidistant apart. Each of these teeth is formed in the shape represented as a flange rising from the rack-head and is adapted to be straddled by the studs 48.

Rotation of the shaft 15 rotates the disk 36, in each rotation of which the finger 38, through the medium of the anti-friction roller 39 upon it, engages a notch 41 in the star-wheel, to move it one step on its axis and, through the idler 44, turn the pinion 45 and the cross-head 47 correspondingly. Thus turning the cross-head engages the stud on one of its ends with the side of the adjacent tooth 49, to rotate the rack on its axis, the stud guidingly following that side of the respective tooth until the opposite stud engages the opposite side of the next adjacent tooth, which then becomes embraced by the two studs. The proportions of the gears 44, 45, relative to the gear 43 is such that turning of the star-wheel the extent of one notch causes the cross-head 47 to make one-half of a revolution. In the position of the cross-head 47 shown in Fig. 3, its engagement with a tooth 49 locks the rack in its position of rest. In this manner the rack is rotated stepwise between reciprocations of the head 20, and its rotations are rendered smooth without jar in starting or stopping, owing to the regular action of its immediate driving-gear. The similar arc-shaped recesses 42 shown to be provided in the periphery of the wheel 40 between the notches 41, by conforming to the arc of the periphery of the disk 36, tend to brake the wheel against undue turning under its inertia in rotating; and the

recess 37 provided in the disk enables it to clear the edges of the notches 41 in the wheel. This gear is an adaptation to the present purpose of the mechanical movement known as the "geneva."

70

While the upper rotatory socket-member 51 of each bottle-clamp is the same in its general function as in the aforesaid patent, it is now equipped with an internal rotary brush for scouring the bottom of a bottle held by it and is rendered vertically extensible and contractible to adapt it to be adjusted to bottles of different diameters.

On a horizontal circumferential flange 52 provided about the edge of the upper rack-head, is seated a ring 53 having external gear-teeth 54 and internal gear-teeth 55.

75

An arc-shaped flange 56 on the under side of the frame-member 16 extends over a considerable portion of the ring 53 to prevent it from rising from its seat. This ring is driven by the large gear 21 meshing with a small gear 57 on a shaft 58 journaled in the frame-member 16 and carrying a pinion 59 meshing with the outer gear 54. At equal intervals about the upper rack-head are journaled in it, near its periphery, one being shown in each tooth 41, spindles 60. Each spindle extends through and beyond a bushing 61, rotatably suspended by a nut 62 surmounting the upper rack-head, and carries on its upper end a pinion 63, below which, and penetrated centrally by the spindle, is a cross-head 64 resting on said nut and having legs 65 depending from its end into sockets 66 formed on the rack-head and in which spiral springs 67 are confined about the legs, tending to raise to its highest position the pinion 63.

85

Into the lower end of each spindle is screwed the stem 69 of a brush-device 68, contained within a bottle-clamp socket 51. Each socket 51 is formed of an outer-ring section 69, having a dished upper end 70 integral with the bushing 61 and containing openings 71, and about which is formed the circumferential flange 72 to engage frictionally with the gears 25, and an inner-ring section 73 provided with a downwardly flaring mouth 74 adapted to fit about the bottoms of bottles 75 of different diameters. Screw-stems 76 project horizontally from diametrically opposite points on the ring 73 through angular slots 77 of zig-zag shape in the ring 69, each slot forming three steps 78, 79 and 80 which afford seats for the stems at different elevations; and the two rings are releasably clamped together by wing-nuts 81 on the screw-stems.

110

Bottles 75 to be washed are confined in inverted position, as in said patented machine, between the lower and upper socket-members 26 and 51 of the clamps; and in the step-by-step rotation of the rack, the pinion 59 drives the gear-ring 53, which, by its engagement with the pinions 63 rotates them

115

120

125

130

to revolve the brushes 68 against the bottoms of the bottles. Water is supplied to the bottom-brushes through a pipe 82 on the frame-member 16, having depending nozzles 83, 84, 5 extending over the path described by the socket-members 51 in the rotation of the rack, to discharge into their dished upper ends and through the latter flow the water upon the bottom-brushes; the pipe 82 having 10 a hose-connection 85 with any of the water-supplying pipes of the machine, as that containing the valve 35. An arc-shaped horizontal track 86, having a cam-end 87, is provided on the bottom of the frame-member 15 16 to extend in the path of the pinions 63 in the rotation of the rack, whereby when a pinion encounters the cam 87, it rides beneath the track 86 and is depressed with its 20 spindle against the resistance of the spring 67 to bear the brush 68 against the respective bottle-bottom; and when the spindle clears the cam-track 86, the springs 67 raise the brush to its normal position. By loosening the wing-nuts 81 on the rings 69, the 25 rings 73 are loosened and may be turned to turn the stems 76 on their seats in the slots 77, and raised and lowered and turned to bring the stems on different seats in said slots. Thus the lower sections 73 of the upper 30 sockets 51 may be readily adjusted with reference to bottles of different diameters, varying within, say, about an inch.

What I claim as new and desire to secure by Letters Patent is—

35 1. In a bottle-washing machine, the combination with the rotatory bottle-rack, of means for rotating it by a step-by-step movement, consisting of a rotatory crank-finger, a notched wheel journaled in position on the frame of the machine to be engaged at the notches in succession by said finger, a circumferential series of uniformly spaced teeth on the upper rack-head, a shaft journaled on said frame and geared to said wheel, 40 and a cross-head on said shaft provided with end-studs adapted to embrace said teeth, one at a time, and work between them, for the purpose set forth.

2. In a bottle-washing machine, the combination with the rotatory bottle-rack, of means for rotating it by a step-by-step movement, consisting of a peripherally recessed rotatory disk carrying a crank-finger, a notched wheel provided with arc-shaped 55 peripheral recesses between the notches and journaled in position on the frame of the machine to be engaged at its notches in succession by said finger, a circumferential series of uniformly-spaced teeth on the upper rack-head, a shaft journaled on said frame and geared to said wheel, and a cross-head on said shaft provided with end-studs adapted to embrace said teeth, one at a time, and work between them, for the purpose set 60 forth.

3. In a bottle-washing machine, the combination with the rotatory bottle-rack, of means for rotating it by a step-by-step movement, consisting of a rotatory crank-finger, a notched wheel on a shaft carrying a gear-wheel and journaled in position on the frame of the machine to cause said finger to engage the notches in succession, one in each rotation of the finger, a circumferential series of uniformly spaced teeth on the upper rack-head, an idler-pinion journaled on said frame to mesh with said gear-wheel, and a pinion journaled to mesh with said idler on a shaft journaled on the frame, and carrying a cross-head provided with end-studs adapted 70 to embrace said teeth, one at a time, and work between them, for the purpose set forth. 75

4. In a bottle-washing machine, the combination with the rotatory bottle-rack, of step-by-step driving means therefor, bottle-clamps each consisting of upper and lower socket-members with a spring-supported bottom-brush rotatably confined in the upper member, gear connections between the rack 80 and brushes for rotating them by the movement of the rack, and a cam in the path of the brush - supports for depressing the brushes against the resistance of their springs, for the purpose set forth. 85

5. In a bottle-washing machine, the combination with the rotatory bottle-rack, of step-by-step driving means therefor, a ring rotatably supported on the upper rack-head, said ring being provided with inner and outer 90 gear-teeth and geared at its outer teeth to said driving means, bottle-clamps having upper rotatable socket-members depending from the said rack-head, brushes in said members on spindles journaled in said head, and pinions on the upper ends of said spindles meshing with said inner teeth on the ring, 95 for the purpose set forth. 100

6. In a bottle-washing machine, the combination with the rotatory bottle-rack, of step-by-step driving means therefor, a ring rotatably supported on the upper rack-head, said ring being provided with inner and outer gear-teeth and geared at its outer teeth to said driving means, bottle-clamps having upper rotatable socket-members depending from 105 said rack-head, brushes in said members on spindles journaled in said head, pinions on the upper ends of said spindles meshing with said inner teeth of the ring, and a water-supply pipe supported to discharge in the path of rotation of said socket-members, for the purpose set forth. 110

7. In a bottle-washing machine, the combination with the rotatory bottle-rack, of step-by-step driving means therefor, a ring rotatably supported on the upper rack-head, said ring being provided with inner and outer gear-teeth and geared at its outer teeth to 120 said driving means, bottle-clamps having 125

upper rotatable socket-members depending from said rack-head, brushes in said members on spindles journaled in said head, pinions on the upper ends of said spindles meshing with said inner teeth of the ring, spring-supported cross-heads under said pinions, and a cam-track in the path of said pinions, for the purpose set forth.

8. In a bottle-washing machine, the combination with the rotatory bottle-rack, of step-by-step driving means therefor, a ring rotatably supported on the upper rack-head, said ring being provided with inner and outer gear-teeth and geared at its outer teeth to said driving means, spring-sockets depending from said head, cross-heads having end-stems entering said sockets, and springs confined in the sockets against said cross-heads, bottle clamps having upper socket-members provided with tubular bushings extending through and rotatably supported on said rack-head, brushes in said members on spindles extending through said bushings, pinions on the upper ends of said spindles above said cross-heads, and a cam-track in the path of said pinions, for the purpose set forth.

9. In a bottle-washing machine, the combination with the rotatory bottle-rack, of a bottle-clamp having its upper socket-member journaled on the upper rack-head to depend therefrom and formed of an outer-ring section and an inner-ring section provided with a downwardly-flaring mouth and adjustable relative to outer-ring section to lengthen and

shorten said member, for the purpose set forth.

10. In a bottle-washing machine, the combination with the rotatory bottle-rack, of bottle-clamps having their upper socket-members formed, each, of an upper ring-section rotatably depending from the upper rack-head and provided with zig-zag seat-forming slots, and a lower ring-section having screw-studs projecting from it through said slots to seat thereon, and nuts on the projecting ends of said stems for clamping the ring-sections in adjusted relation, for the purpose set forth.

11. In a bottle-washing machine, the combination with the rotatory bottle-rack, of bottle-clamps having their upper socket-members formed, each, of an upper ring-section containing zig-zag seat-forming slots and provided with a dished upper portion at which it is rotatably supported on the upper rack-head to depend therefrom, and a lower ring-section provided with a flaring mouth for receiving a bottle-bottom and having screw-studs projecting laterally from it through said slots to seat therein, with nuts on the projecting ends of said stems for clamping the ring-sections in adjusted relation, and rotatably supported brushes in said socket-members, for the purpose set forth.
